Patented May 23, 1922.

UNITED STATES PATENT OFFICE.

HERMAN A. STEIN, OF GEORGETOWN, MINNESOTA.

FANNING MILL.

1,417,469.

Specification of Letters Patent. Patented May 23, 1922.

Application filed July 21, 1921. Serial No. 486,365.

To all whom it may concern:

Be it known that I, HERMAN ARTHUR STEIN, a citizen of the United States, and a resident of Georgetown, in the county of 5 Clay and State of Minnesota, have invented a new and Improved Fanning Mill, of which the following is a full, clear, and exact description.

This invention relates to a fanning mill 10 for use in cleaning grain.

The object of this invention is to provide a grain cleaner which may be adapted to the cleaning of all ordinary grains by the changing of sieves.

15 A further object is to construct a machine which cleans the grain in stages and which has a larger screening area than is generally used so as to give more perfect cleaning.

This object is accomplished by first passing the grain through a grating against an air blast and providing means for carrying away all dirt separated from the grain, then passing the grain over a plurality of overlapping sieves against which an air blast 25 is directed, and finally over a screen.

The invention will be more clearly understood in the following detailed description and accompanying drawings.

Figure 1 is a side elevation of the fanning 30 mill;

Figure 2 is a vertical cross section;

Figure 3 shows the lever for operating the adjustable feed board;

Figure 4 is a section along the line 4—4 of 35 Figure 2; and

Figure 5 is a perspective view of the carrier and the tightening means.

Referring to the above-mentioned figures, the frame 10 carries a hopper 11 and a fan 40 casing 12. Mounted in the fan casing is a shaft 13 to which is fixed a fan 14. Located below the hopper 11 is a feed board 16 having a rod 20 fixed to the end. Co-operating with the feed board 16 and serving to adjust it is a wire lever 17. The lever 17 has a portion 20 bent at right angles to the lever arm and extending through an opening 18 in the side board of the fanning mill. The opening 18 serves as a bearing in which 50 the portion 20 rotates as the lever arm is operated. On the end of the portion 20 is a forked member 19 fitting over the feed board 16 and which may be fixed to it in any manner such as riveting. The amount of grain 55 entering the mill may be regulated by tilting the feed board through the operation

of the lever 17. Mounted on the end board of the hopper is a bracket 21 which has a number of notches therein into which the lever 17 fits and which serves to retain the 60 lever in any desired position.

A force feed roller 15 is rotatably mounted just below the opening in the hopper. Fixed to the hopper support and located below the feed roller 15 is a fork member consisting of grating rods 22. Co-operating with the grating rods 22 is a spout 55 and a carrier 23 turned by means of rollers 24 and 25. In conjunction with roller 25 means for tightening the carrier are provided. This tightening means consists of stepped irons 26 which are attached to the ends of the side boards by means of screws 29. These members 26 have openings in one end through which eyebolts 27 project. The roller 25 is mounted in the eyebolts and thumb nuts 28 engage with the eyebolts and may be used for tightening the carrier belt 23.

A shaker 30 has one end supported by means of hangers 31 which are connected with the frame at 32. The other end of the shaker 30 is carried by members 33 pivoted to it at 34. These members 33 are supported by frame 10 to which they are pivoted at 35. The rod 56 extends across the shaker 30 and serves as a support for the sides of the shaker. The second shaker 36 is carried by means of members 33 and hangers 37.

A number of sieves 38 are fastened in the shaker 30. When it is desired to clean wheat, a series of eight sieves 38 are provided, as shown in Figure 2. When the machine is to be used for cleaning oats or barley the eight sieves are removed and two suitable sieves are inserted in the shaker 30. Thus it is seen for different grains different combinations of sieves are selected. A screen 39 is mounted in the shaker 36. Fixed to the bottom of the shaker 30 is a screenings slide 40. The bottom of the shaker 30 is cut off at 41 to allow the grain to drop into the shaker 36.

A pulley 44 having an eccentric pin 46 is mounted on the shaft 13. This eccentric pin is connected to a projection 45 on one of the members 33 by means of a connecting rod 50. It will be seen that the rotation of shaft 13 will serve to operate the shakers 30 and 36.

Co-operating with the fan casing 12 is a door 42 which may be rotated about shaft

13 to open the casing to allow air to be drawn in upon the rotation of the fan. This door may be fixed in any position by means of a thumb nut 43. Two flues 58 and 59 are provided in conjunction with the fan casing 12. The flue 58 directs an air blast along the carrier 23, while flue 59 directs an air blast underneath the sieves 38. A key 57 is provided in flue 59 to control the air blast passing therethrough.

A small sprocket wheel 54 is fixed to the shaft 13. A large sprocket wheel 48 is mounted on the shaft of the feed roller 15 and mounted on roller 24 is a pulley 47. The sprocket wheel 48 is connected to the sprocket wheel 54 by means of a chain 49. The pulley 47 mounted on the roller 24 is connected by means of a crossed belt 51 to a small pulley 52 mounted on the shaft 13. When it is desired to operate the fanning mill by hand a crank 53 is fixed to the shaft of the force feed roller 15. If it is desired to operate the fanning mill by a power drive the sprocket wheels 48 and 52 are removed along with the chain 49. A pulley of the proper size is then mounted on the shaft 13 and this pulley is driven direct from the power drive. A small pulley is mounted on the shaft of the force feed roller 15 and is connected by means of a crossed belt with the pulley 47 fixed to the roller 24.

The operation of the machine is as follows:

The grain to be cleaned is thrown into the hopper 11 and the crank 53 turned. As the force feed roller 15 is rotated its rotary motion is conveyed through sprocket wheel 48, chain 49 and sprocket wheel 54 to the shaft 13, thus operating the fan. The pulley 52 which is mounted on the shaft 13 rotates with it, and through the crossed belt 51 rotates the pulley 47 driving the roller 24. It will be seen that the roller 24 rotates in the opposite direction to the force feed roller 15. The rotation of the shaft 13 rotates the pulley 44 on which is mounted the eccentric pin 46 and thus by means of the rod 50 which is connected to the member 33 the shakers 30 and 36 are operated.

As the fan 14 is rotated it creates an air blast. This air blast may pass through the flues 58 or 59. The strength of the air blast can be controlled by the operation of the door 42. The current of air passing through flue 59 can be controlled by means of key 57.

The grain in hopper 11 is drawn down by means of force feed roller 15 and drops through the grating rods 22 against the air blast directed along the carrier by flue 58. All large pieces of dirt are removed from the grain by means of the grating rods 22 and are carried into the spout 55 by the carrier 23. Chaff and light pieces of dirt are blown into the spout 55 by means of the air blast passing through the flue 58. The amount of

grain that passes down into the machine may be controlled by means of the feed board 16 which is operated by the lever 17. The grain, due to its weight, slides down the carrier 23 and upon the sieves 38 and as it passes over the sieves all small seeds drop through them and are carried away by slide 40. The air blast passing through flue 59 blows out of the machine all chaff and light dirt that may be in the grain when it reaches sieves 38. Next, the grain passes onto the screen 39 carried by the shaker 36, and here the final screening takes place and the grain is passed out of the machine.

Claims:

1. A grain cleaner comprising a feed roller, a plurality of grating rods located below the feed roller, a fan for creating an air blast and a flue for directing it up through the forks, a carrier co-operating with the forks to carry the dirt out of the machine, a plurality of overlapping sieves carried by a shaker positioned below said carrier, and a second flue for directing an air blast through them. 90

2. A grain cleaner, comprising a frame, a hopper and a feed roller mounted on the frame, a grating located below said feed roller, a carrier and slide provided in conjunction with the grating for carrying off the coarser dirt stopped by the grating, a fan for creating an air blast co-operating with the carrier and grating to blow off the grain the finer dirt, a plurality of removable sieves carried by the shaker located below said carrier and means for passing a regulable air blast through them, means for operating the fan, and means connecting the fan to the carrier, feed roller and shaker to operate them. 95

3. A grain cleaner comprising a fan shaft and a fan mounted thereon, a feed roller connected to said fan shaft, a fork located below the feed roller, a carrier driven by the force feed roller shaft co-operating with the fork to remove the coarser dirt, a flue for directing an air blast along the carrier and up through the fork for blowing the finer dirt, a plurality of shakers, operated from the fan shaft, supported beneath the carrier, a plurality of sieves removably fastened in the top shaker and a flue for directing a regulable air blast through them. 105

4. A grain cleaner comprising a frame, a hopper and fan casing carried by the frame, a door for controlling the amount of air entering the casing, a feed roller located below the hopper, a fork supported beneath the feed roller, a carrier and slide co-operating with the fork to remove the coarser dirt caught by them, a fan mounted in the fan casing to create an air blast, a flue for directing the air blast up through the fork, a plurality of shakers supported by the frame, a series of sieves removably fastened 120

in the top shaker, a second flue for directing an air blast through them, a key located in the second flue for controlling the air blast.

5. A grain cleaner comprising a frame, a hopper carried by the frame, an adjustable feed board co-operating with the hopper, a lever connected to the feed board for adjusting it, a feed roller arranged adjacent the feed board, a fork located below the feed roller, a carrier co-operating with the fork operated by the rotation of the feed roller, a fan for creating an air blast and a flue for directing it up through the fork, a pair of shakers operated from the feed roller shaft, a plurality of sieves removably fastened in the top shaker

and a flue for directing an air blast through them.

6. As a new article of manufacture, a grain cleaner comprising a feed roller, a grating located below the feed roller, a carrier co-operating with the grating to remove dirt and to delay the progress of the grain to the sieves, a fan for creating an air blast and a flue in conjunction therewith for directing the air blast against the grain as it enters the machine, a plurality of overlapping sieves located below the grating, a second flue co-operating with the fan to direct an air blast up through the sieves, and means for controlling the air blasts through both flues.
